(57) **CLAIM**

The ornamental design for a set of tobacco heating device and charger, as shown and described.

DESCRIPTION

FIG. 1 is a perspective view of a set of tobacco heating device and charger showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view with the lid pulled out for a clarity of disclosure thereof; and,

FIG. 9 is another perspective view in the state of use thereof. The broken lines in FIG. 9 illustrate environmental subject matter that form no part of the claimed design.

1 Claim, 9 Drawing Sheets
